[57] CLAIM

The ornamental design for a syringe pump, as shown.

DESCRIPTION

FIG. 1 is a front perspective view of a syringe pump showing our new design;

FIG. 2 is a front elevational view of the syringe pump shown in FIG. 1;

FIG. 3 is a left side elevational view of the syringe pump shown in FIG. 2;

FIG. 4 is a right side elevational view of the syringe pump shown in FIG. 2;

FIG. 5 is a rear elevational view of the syringe pump shown in FIG. 2;

FIG. 6 is a top plan view of the syringe pump shown in FIG. 2; and,

FIG. 7 is a bottom plan view of the syringe pump shown in FIG. 2.

FIG. 1
